UNITED STATES PATENT OFFICE.

DAVID ELDREDGE CROUSE, OF ANNAPOLIS, MARYLAND.

DEVICE FOR STARTING INTERNAL-COMBUSTION ENGINES.

1,032,274.

Specification of Letters Patent.

Patented July 9, 1912.

Application filed September 21, 1911. Serial No. 650,490.

To all whom it may concern:

Be it known that I, DAVID E. CROUSE, a citizen of the United States, and a resident of Annapolis, in the county of Anne Arundel and State of Maryland, have made certain new and useful Improvements in Devices for Starting Internal-Combustion Engines, of which the following is a specification.

10 My invention relates to devices for starting internal combustion engines, and it consists in the constructions, combinations and arrangements herein described and claimed.

An object of my invention is to provide a 15 device which will permit the starting of the engine through the action of a spring under tension, and which will restore the spring to its original position after the engine is started.

20 A further object of my invention is to provide a device in which the starting of the engine is accomplished by the movement of a rack into engagement with a pinion, with means for swinging the rack out of engagement with the pinion and causing its 25 return to its original position, thereby permitting the pinion to turn freely with the engine shaft.

A further object of my invention is to 30 provide means carried by the rack for operating the air valves.

Other objects and advantages will appear in the following specification and the novel features of the device will be particularly 35 pointed out in the appended claims.

My invention is illustrated in the accompanying drawings forming part of this application in which similar reference characters indicate like parts in the several views, 40 and in which—

Figure 1 is a side view of the device, one of the valves being shown in section, Fig. 2 is a longitudinal section through the device, Fig. 3 is an end view of the device, Fig. 4 is a section along the line 4—4 of Fig. 2, and Fig. 5 is a section along the line 5—5 of Fig. 2.

In carrying out my invention I provide a main cylinder 1 which is suitably supported in any convenient position. Arranged to extend through the cylinder is a piston rod 2 to which the piston 3 is attached. Disposed between the piston 3 and one end of the cylinder 1 is a spiral spring 4.

55 A rack 5 is pivotally connected with the piston rod 2 by means of the arms 5^a—5^b.

The rack 5 is arranged to engage a gear 6 on the shaft 7 of the engine (not shown). A trip 8 is normally held in engagement with the end 2^a of the piston rod 2 by means of a spring 9, which bears against a stationary plate 10.

At 11 I have shown a main valve chest which contains a slide valve 12, provided with arms 12^a and 12^b, extending through opposite ends of the chest. At 13 and 14 are ports each connecting with a pipe 15, leading to an auxiliary cylinder 16. The port 13 and an exhaust pipe 17 are adapted to be brought into communication by means of the passage 12^c in the valve 12. A pipe 18 which is connected to a compressed air supply (not shown) has a branch 19 which may communicate with the passage 12^c in the valve 12. A pipe 20 leads to an auxiliary valve chest 21, which is connected with the opposite end of the main cylinder 1 by means of the pipe 22.

Within the cylinder 16 is a piston 23 against which a spring 24 bears. The piston rod 25 has a pivoted connection 26, which is pivotally connected with the extension 5^x of the rack 5 at 27. In order to guide the rack in its movement, I provide a plate 28 having an arc-shaped slot 28^a, as shown in Figs. 3 and 4. At one end of the slot 28^a is the valve stem 29 of a valve 30, which is normally held by means of a spring 31, downwardly in the position shown in Fig. 1. This valve is provided with a port 30^a adapted to be brought into registration with the pipe 22 when the valve is raised, and a recess 30^b which normally connects the pipe 22 with an exhaust opening 30^c.

From the foregoing description of the 95 various parts of the device the operation thereof may be readily understood.

Consider the apparatus in the position shown in Figs. 1 and 2 with the engine “dead”. The operator releases the trip 8 by pulling upwardly thereon. A spring 4 is under tension and suddenly drives forward the piston 3, the air escaping through the pipe 22, the recess 30^b in the valve 30, and the exhaust opening 30^c. The rack in 105 its forward movement engages the pinion 6, causing the revolution of the shaft 7 and the starting up of the engine. The rack passes entirely out of engagement with the pinion. When the arm 33 on the bar 34 engages the 110 stem 12^a of the valve 12, the latter is shifted so as to permit the entrance of air from

the pipe 18, through the port 14 into the pipe 15, and thence into the cylinder 16. The air drives forward the piston 23 in the latter cylinder, thereby swinging the rack laterally on its pivots. As soon as the bar 5^x comes into engagement with the lower end of the valve stem 29, the valve 30 is shifted upwardly against the tension of the spring 31, thereby cutting off the exhaust 30^e and permitting the compressed air to enter through the valve casing 21, thence by pipe 22 to the end of the cylinder 1. This forces back the piston and carries the rack toward the rear. The spring 4 is compressed. As soon as the piston rod 2 clears the end of the trip 8, the latter drops down into place, thereby locking the piston rod in position with the spring 4 compressed. The bar 5^x slides through the pivoted link connection 26. As soon as the arm 36 on the bar 34 engages the valve stem 12^b, the valve 12 is brought into the position shown in Fig. 2 and the air will escape from the cylinder 16 by means of the pipe 15, ports 13, 12^b, and 25 by the exhaust 17, being driven out by means of the spring 24 in the cylinder 16. The rack is therefore swung downwardly into its original position, and the device is reset for again starting the engine.

30 I claim:

1. In a device for starting internal combustion engines, a pinion on the engine shaft, a slidable rack arranged to engage said pinion, means for moving said rack into engagement with said pinion, means for swinging the rack laterally out of the plane of the pinion, means for retracting the rack when out of alinement with the pinion, and means for swinging the rack into its original position.

40 2. In a device for starting internal combustion engines, a pinion on the engine shaft, a pivoted rack arranged to engage said pinion, a spring for moving said rack into engagement with said pinion, pneumatic means for swinging the rack out of alinement with said pinion, means for retracting the rack when out of alinement with the pinion, and

a second spring for swinging the rack into its original position.

3. In a device for starting internal combustion engines, a pinion on the engine shaft, a pivoted rack arranged to engage said pinion, a spring for moving said rack into engagement with said pinion, pneumatic means for swinging the rack out of alinement with said pinion, pneumatic means for retracting the rack when out of alinement with the pinion, and for compressing said spring, and a second spring for swinging the rack into its original position.

4. In a device for starting internal combustion engines, a pinion on the engine shaft, a pivoted rack arranged to engage said pinion, a spring for moving said rack into engagement with said pinion, pneumatic means for swinging the rack out of alinement with said pinion, pneumatic means for retracting the rack when out of alinement with the pinion and for compressing said spring, a second spring for swinging the rack into its original position, and a pair of valves for conjointly controlling both of said pneumatic means, each of said valves being actuated by the movement of the rack.

5. In a device for starting internal combustion engines, a pinion on the engine shaft, a pivoted rack arranged to engage said pinion, a spring for moving said rack into engagement with said pinion, pneumatic means for swinging the rack out of alinement with said pinion, pneumatic means for retracting the rack when out of alinement with the pinion and for compressing said spring, a second spring for swinging the rack into its original position, and a pair of valves for conjointly controlling both of said pneumatic means, one of said valves being actuated by the movement of the rack in one direction and the other being actuated by the movement of the rack in the reverse direction.

DAVID ELDRIDGE CROUSE.
